UNITED STATES PATENT OFFICE.

JOHN MCE. AMES, OF DUNGAN HILLS, NEW YORK, ASSIGNOR TO AMERICAN CAR AND FOUNDRY COMPANY, OF ST. LOUIS, MISSOURI, A CORPORATION OF NEW JERSEY.

SIDE FRAME FOR TRUCKS.

1,021,125.

Specification of Letters Patent.

Patented Mar. 26, 1912.

Application filed December 9, 1910. Serial No. 596,542.

To all whom it may concern:

Be it known that I, JOHN MCE. AMES, residing at Dungan Hills, Staten Island, New York, and being a citizen of the United States, have invented certain new and useful Improvements in Side Frames for Trucks, of which the following is a full, clear, and exact description, such as will enable others skilled in the art to which it applies to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is an elevational view of a side frame constructed in accordance with my invention, said view showing the inner side of the frame. Fig. 2 is an enlarged horizontal sectional view of approximately one-half of the structure shown in Fig. 1, said section being taken substantially on the plane of line 2—2 of Fig. 1. Figs. 3, 4 and 5 are detail sectional views taken respectively on the planes of lines 3—3; 4—4 and 5—5 of Fig. 1, and Fig. 6 is a detail view of one of the reinforcing castings.

The object of this invention is to provide a side frame for car trucks wherein the principal parts are formed of sheet metal pressed into desired shape; further to employ two sheets of metal spaced apart, each of said sheets being formed with marginal flanges and one of said sheets being adapted to fit between the flanges of the other in such manner as to dispose the flanges of the two sheets parallel and in direct contact so that they may be welded or otherwise secured together and thus produce a double thickness of solid metal throughout the principal outlines of the structure.

A further object is to provide reinforcing castings for those portions of the structure which are designed to extend above the journal boxes of the truck and to form said castings into substantial supports for the usual brake hanger brackets.

A further object is to provide for suit-

able openings in the side frame, through which the intermediate mechanism of the truck proper; that is, the parts of the truck between the side frames, may be readily observed and to so arrange the several flanges of the frame that these openings may be provided without detracting from the ultimate strength of the side frame.

Referring to the parts by numerals, 1—1 indicates the customary journal boxes; 2—2 the axles and 3 the bottom or tension tie rod of ordinary truck construction, which parts are of the usual construction and are illustrated simply to show their positions relative to the special side frame of this invention.

The invention resides in the structure of the main side frame, of which the top or compression chord 4 extends continuously from one journal box to the other and is arched as is common in such structures. The lower or tension chord 5 of the side frame is formed with a central horizontal portion 6 for supporting the usual spring plank of the truck and the opposite ends of said chord beyond the portions 6 are extended obliquely upward and merge into the upper chord 4 near the respective journal boxes. The usual central opening as 7 is formed for the reception of the ends of the truck bolster.

The two pressed members comprising the principal parts of the structure and designated by the numerals 8 and 9 are each formed of a single piece of sheet metal provided with upper and lower marginal flanges conforming to the outline just described. Each member is formed also with a central aperture and each of said apertures is flanged, the flanges of which being of equal depth with the marginal flanges of the respective members. The central aperture of the member 9 is preferably rectangular in shape and is relatively smaller than the central aperture of the member 8 and forms the opening 7 above mentioned with upper and lower horizontal flanges 10—10 lapping and secured to upper and lower horizontal flanges 11—11 of the member 8 and with vertical flanges 12—12 for confining the spring plank and for supporting the opposite bolster guides or rub plates 13—13.

The central aperture of the member 8 is extended at its opposite sides so that its oblique inner flanges 14-14 are disposed parallel with the inclined portions of its outer marginal flanges. The flanges of the member 9 are deeper than the flanges of the member 8 and the respective members are placed in the structure with their webs or body portions spaced apart and with the outer edge of the 10 several flanges in a single vertical plane as clearly illustrated in Fig. 5 of the drawings.

Reinforcing castings as 15-15 are disposed between the members 8 and 9, and those parts of said castings which lie in the 15 portions of the structure which extend above the journal boxes are fitted between the spaced webs of the respective members 8 and 9 and between the upper and lower flanges of the member 9, they being secured 20 by long rivets 16 which extend through said castings and through the webs of said members. (See Figs. 2 and 3). These portions of the castings are formed with suitable vertical apertures as 17 for the reception of 25 the usual vertical bolts employed for securing the journal boxes in position. The inner end of each of the castings is formed with an upper and lower wall 18-18 flared so as to rest in close contact with and between the converging adjacent portions of 30 the upper and lower flanges of the member 9. Each of said inner ends is also formed with a vertical side wall 19 connecting the flared walls 18 and extending to the adjacent side of the adjacent vertical flange 12 35 of the member 9, where it is formed into a heavy flange 20 for reinforcing the flange 12 and assisting in the support of the adjacent bolster guide 13 which is positioned upon the opposite side of the flange 12, or within 40 the opening 7, and is held by suitable rivets extending through the flange 20 and through the intervening portion of the flange 12.

45 Between the flange 20 and the flared walls 18 each of the castings 15 is formed with an aperture as 21 of sufficient size to permit of ready inspection of the parts of the truck structure which lies adjacent the opposite sides of the bolster, and which would otherwise be hidden against inspection from the outer side of the truck. The walls of the aperture are flanged as at 22, said flange engaging and serving to reinforce adjacent 50 portions of the side flanges of the central aperture of the member 8. Connecting flanges or ribs as 23-23 are extended from the flange 22 to the flange 20 for reinforcing the latter. The web of the member 9 is 55 of course cut away to conform to the shape of the aperture 21.

The inner ends of each of the castings are secured to the members 8 and 9 by rivets 24 which extend through the spaced webs of said members and through suitable

embossments or spacing lugs formed upon said casting. Other rivets as 25 extend through the side wall 19 of said casting and through the web of the member 9 only at points spaced around the aperture 21.

70 Each of the bolster guides 13 is formed with a flange as 26 which laps the inner edge of the flange 12 and is reinforced by suitable ribs as 27 for supporting the inwardly extending ears or brackets 28 which 75 brackets are designed to support the usual brake hanger, not illustrated.

Having thus described my invention, what I claim as new and desire to secure by Letters Patent is:

80 1. A side frame structure for trucks comprising a pair of juxtaposed flanged members and each of said members being shaped to form separated compression and tension chords.

85 2. A side frame structure for trucks comprising a pair of juxtaposed pressed flanged members extending continuously from end to end of the structure, and each of said members being shaped to form separated compression and tension chords.

90 3. A side frame structure for trucks comprising a pair of juxtaposed members, and each of said members being provided with an opening adapted to receive the truck 95 bolster.

95 4. A side frame structure for trucks comprising a pair of juxtaposed members, and each of said members being provided with an opening adapted to receive the truck 100 bolster and bolster guides secured to one of said members.

105 5. A side frame structure for trucks comprising a pair of juxtaposed members, one of said members being formed with a plurality of openings, one of said openings being adapted to receive the truck bolster and the other of said members being formed with an opening adapted to surround all of the openings in said first member.

110 6. A side frame structure for trucks comprising a pair of juxtaposed flanged members, one of said members being adapted to fit between the flanges of the other member, and one of said members being provided 115 with an opening adapted to receive the truck bolster.

115 7. A side frame structure for trucks comprising a pair of flanged members, one of said members being adapted to fit between the flanges of the other member, and the flanges of the two members being in contact and being adapted to be welded or otherwise secured together throughout the 120 entire upper and lower margins of the 125 structure.

120 8. A side frame structure for trucks comprising a pair of members, each of said members being formed with a flanged aperture, the flanges of the respective apertures 130

- being partly in contact and partly spaced apart, and one of said members being formed with an aperture opening into the space between the said flanges.
5. 9. In a side frame structure for trucks, a pressed member comprising integral spaced compression and tension chords forming an aperture adapted to receive the truck bolster, and an overlapping member, both members providing spaced apertures disposed upon opposite sides of said first aperture adapted for examination of the structure of the truck through the side frame.
10. 10. A side frame structure for trucks comprising a member formed with a flanged aperture adapted to receive the truck bolster, and a brake hanger bracket fixed to the flange of said aperture.
11. 11. A side frame structure for trucks comprising a member formed with a flanged aperture adapted to receive the truck bolster and a combined bolster guide and brake hanger fixed to the flange of said aperture.
12. 12. A side frame structure for trucks comprising a pair of members, one of said members being formed with a plurality of openings, each of said openings being provided with a flange and the other of said members being provided with a flanged opening, the flange of which is adapted to engage the flanges of all of the openings in the other member.
13. 13. A side frame structure for trucks comprising a member formed with a plurality of apertures and reinforcing members formed each with a flanged aperture and each of said apertures being adapted to register with one of the apertures in said other member.
14. 14. A side frame structure for trucks comprising a member formed with a plurality of apertures, brake hanger brackets supported in one of said apertures, supports for said brake hanger brackets, and members adapted to reinforce the supports of said brake hanger brackets, each of said reinforcing members being formed with a flanged aperture, and each of said apertures being adapted to register with one of said first mentioned apertures.
15. 15. In a side frame structure for trucks, a member comprising a main body portion formed with an aperture adapted to receive the truck bolster, and with a portion adapted to project above the journal box of the truck, a member adapted to reinforce the connection between the last mentioned portion and said body portion and a brake hanger bracket supported in said aperture, said reinforcing member being adapted to partly support said brake hanger bracket.
16. 16. A side frame structure for trucks comprising a pair of flanged members, one of said members being adapted to fit between the flanges of the other member and all of
17. 17. In a side frame structure for trucks, a pair of spaced members comprising a main body portion formed with an aperture adapted to receive the truck bolster, and with a portion adapted to project above the journal box of the truck, a member disposed between said spaced members and being adapted to reinforce the connection between the body portion and said projecting portion and a brake hanger bracket supported in said aperture, said reinforcing member being adapted to partly support said brake hanger bracket.
18. 18. A side frame structure for trucks comprising a pair of marginally flanged members, one of said members being adapted to fit between and partly in contact with the flanges of the other member, each of said members being formed with a flanged aperture, the flanges of the apertures being partly in contact and all of said contacting flanges being adapted to be welded or otherwise secured together.
19. 19. A side frame structure for trucks comprising a pair of closely juxtaposed flanged members spaced apart substantially an even distance throughout their length, having an opening adapted to receive the truck bolster.
20. 20. A side frame structure for trucks comprising a pair of juxtaposed members, each being shaped to form separated compression and tension chords, said chords merging adjacent the ends of said members.
21. 21. A side frame structure for trucks comprising a pair of closely juxtaposed members, each being shaped to form spaced compression and tension chords and one of said members being provided with an opening adapted to receive the truck bolster.
22. 22. A side frame structure for trucks comprising a plurality of juxtaposed members, each of said members being formed with an aperture adapted for examination of the structure of the truck through the side frame.
23. 23. A side frame structure for trucks comprising a plurality of juxtaposed members, one of said members being formed with an aperture adapted to receive the truck bolster, and each of said members being formed with an aperture adapted for examination of the structure of the truck through the side frame.
24. 24. A side frame structure for trucks comprising a plurality of juxtaposed members, one of said members being formed with an aperture adapted to receive the truck bolster, and the other of said members being formed with an opening adapted for examination of the structure of the truck through the side frame.
25. 25. A side frame structure for trucks comprising a plurality of juxtaposed mem-

bers, one of said members being formed with an aperture adapted to receive the truck bolster and the other of said members being formed with an aperture opening into the aperture in said first member adapted for examination of the structure of the truck through the side frame.

26. A side frame structure for trucks comprising a pair of juxtaposed members, each of said members being provided with an opening adapted to receive the truck bolster, and one of said members being formed with an opening adapted for examination of the structure of the truck through the side frame.

27. A side frame structure for trucks comprising a plurality of juxtaposed flanged members extending the length of said structure, and one of said members being formed with an opening adapted to receive the truck bolster.

28. A side frame structure for trucks comprising a plurality of juxtaposed flanged members, and one of said members being formed with a plurality of openings adapted for examination of the structure of the truck through the side frame.

29. A side frame structure for trucks comprising a plurality of juxtaposed flanged members, and one of said members being formed with a plurality of openings, one of said openings being adapted to receive the truck bolster and others of said openings being adapted for examination of the structure of the truck through the side frame.

30. A side frame structure for trucks comprising a plurality of juxtaposed flanged members, one of said members being formed with a plurality of openings, one of said openings being adapted to receive the truck bolster, and others of said openings being adapted for examination of the structure of the truck through the side frame, and the other of said members being formed with an opening adapted to surround all of the openings in said first member.

31. In a single side frame structure for trucks, a combination comprising a channel shaped member of variant cross section extending from end to end of the structure and having an opening adapted to receive the truck bolster and a second channel shaped member within and in flange contact with said first mentioned channel shaped member.

32. In a single side frame structure for trucks, a combination comprising a channel shaped member of variant cross section having an opening in its web formed with a flange adapted to coöperate with the flanges of said channel to form spaced compression and tension chords and a second channel shaped member within and in flange contact

with said first mentioned channel shaped member.

33. In a single side frame structure for trucks, a combination comprising a channel shaped member of variant cross section having an opening in its web with a flange adapted to coöperate with the flanges of said channel to form spaced channel shaped compression and tension chords and a second channel shaped member within and in flange contact with said first mentioned channel shaped member.

34. In a single side frame structure for trucks, a combination comprising a plurality of channel shaped members in flange contact and of variant cross section, each being formed with an opening adapted to receive the truck bolster.

35. A side frame structure for trucks comprising a plurality of channel shaped members in flange contact and of variant cross section, each being formed with an opening adapted for examination of the structure of the truck through the side frame.

36. In a single side frame structure for trucks, a combination comprising a plurality of channel shaped members in flange contact and of variant cross section, one of said members being formed with an opening adapted to receive the truck bolster.

37. In a single side frame structure for trucks, a combination comprising a pair of channel shaped members in flange contact and of variant cross section, being spaced apart, and one of said members being formed with an opening adapted to receive the truck bolster.

38. A side frame structure for trucks comprising a channel shaped member of variant cross section, and a reinforcing member extending approximately from end to end thereof being received between the flanges of said channel member.

39. In a single side frame structure for trucks, a combination comprising a channel shaped member of variant cross section having an aperture adapted to receive the truck bolster, and a reinforcing member in flange contact with said channel extending upon opposite sides of said aperture.

40. A side frame structure for trucks comprising a channel shaped member of variant cross section having an aperture adapted to receive the truck bolster and having an aperture adapted for examination of the structure of the truck through the side frame, and a reinforcing member surrounding said apertures, said reinforcing member fitting between the flanges of said channel member.

41. A side frame structure for trucks comprising a channel shaped member of variant cross section, and a channel shaped member fitting between the flange of said

first member and being spaced from the web thereof, the flanges of said members contacting throughout their length.

42. A side frame structure for trucks comprising a channel shaped member of variant cross section having a flanged opening adapted to receive the truck bolster, and a reinforcing member having an aperture surrounding said first mentioned aperture 10 having a flange contacting with and being fixed to the flange of said first aperture.

43. A side frame structure for trucks comprising a pair of closely juxtaposed members, means connecting said members, 15 and a brake hanger bracket fixed to said connecting means.

44. A side frame structure for trucks comprising a pair of closely juxtaposed members, a reinforcing member for said 20 structure extending between and connecting said members, and a brake hanger bracket fixed to said reinforcing member.

45. A side frame structure for trucks comprising a plurality of closely juxtaposed 25 members, means connecting said members, said connecting means being formed with an aperture adapted for inspection of the structure of the truck through the side frame.

46. A side frame structure for trucks comprising a pair of closely juxtaposed members, and a reinforcing member for said 30 structure extending between and connecting said members, said reinforcing member being formed with an aperture adapted for 35 inspection of the structure of the truck through the side frame.

47. A side frame structure for trucks comprising a pair of channel shaped members of variant cross section, each being formed 40 with an opening adapted to receive the truck bolster, one of said members being disposed between the flanges of the other member.

48. A side frame structure for trucks comprising a member formed with an aperture 45 adapted to receive the truck bolster, and a combined bolster guide and a brake hanger bracket supported in said aperture.

49. In a single side frame structure for trucks, a combination comprising a pair of 50 channel shaped members of variant cross section having apertures adapted to receive the truck bolster, and reinforcing members between said channel members at opposite sides of said apertures.

50. A side frame structure for trucks comprising a pair of channel shaped members of variant cross section having apertures adapted to receive the truck bolster, and reinforcing members at opposite sides of said 55 apertures, said reinforcing members extending into the aperture of one of said members, and said extended portions being each formed with an aperture adapted for examination of the structure of the truck 60 through the side frame.

51. In a side frame structure for trucks, the combination with a member comprising a compression and a tension chord, of a reinforcing member therefor formed with an aperture adapted for examination of the 70 structure of the truck through the side frame.

52. In a side frame structure for trucks, the combination with a member comprising compression and tension chords, of a 75 separately formed reinforcing member therefor and a brake hanger bracket fixed to said reinforcing member.

53. In a side frame structure for trucks, the combination with a member comprising 80 compression and tension chords, of a separately formed reinforcing member therefor, and a combined brake hanger bracket and bolster guide fixed to said reinforcing member.

54. In a side frame structure for trucks, the combination with a member comprising a body portion and a supporting arm adapted to extend above a journal box of the truck, of a reinforcing member extending 90 between said body portion and arm formed with an aperture adapted for examination of the structure of the truck through the side frame.

55. In a side frame structure for trucks, 95 the combination with a member comprising a body portion and a supporting arm adapted to extend above a journal box of the truck of a separately formed reinforcing member extending between said body 100 and arm, and a brake hanger bracket fixed to said reinforcing member.

56. In a side frame structure for trucks, the combination with a channel shaped member of variant cross section comprising a 105 body portion and a supporting arm adapted to engage a journal box of the truck, of a reinforcing member extending between said body portion and arm, and being disposed between the flanges of said channel 110 member.

57. In a side frame structure for trucks, the combination with a channel shaped member of variant cross section comprising a body portion and supporting arms adapted 115 to engage the journal boxes of the truck, of a reinforcing member extending between said body portion and arms and comprising spaced compression and tension chords.

58. In a side frame structure for trucks, the combination with a channel shaped member of variant cross section comprising a body portion and supporting arms adapted to engage the journal boxes of the truck, of a reinforcing member extending between 125 said body portion and arms and comprising spaced channel shaped compression and tension chords.

59. A side frame structure for trucks comprising a body portion and a hollow sup- 130

- porting arm adapted to engage a journal box of the truck, a reinforcing member fixed to said body portion and extending into said arm, and a brake hanger bracket fixed to 5 said reinforcing member.
60. A side frame structure for trucks comprising a body portion and a hollow supporting arm adapted to engage a journal box of the truck, a reinforcing member fixed 10 to said body portion and extending into said arm, and a bolster guide fixed to said reinforcing member.
61. A side frame structure for trucks comprising a pair of channel shaped members 15 of variant cross section forming a body portion having tubular arms adapted to engage the journal boxes of the truck, one of said members being apertured to receive the truck bolster.
62. A side frame structure for trucks comprising a pair of channel shaped members 20
- of variant cross section forming a body portion having tubular arms adapted to engage the journal boxes of the truck, and reinforcing members fixed to said body portion and extending into said arms. 25
63. A side frame structure for trucks comprising a pair of channel shaped members of variant cross section forming a body portion having tubular arms adapted to engage 30 the journal boxes of the truck, reinforcing members fixed to said body portion and extending into said arms, and means extending through and connecting said channel members to said reinforcing members. 35

In witness whereof I have hereunto set my hand in the presence of two witnesses.

JOHN McE. AMES.
